United States Patent

Des. 237,884
Patented Dec. 2, 1975

237,884

WATER CLOSET

Stanley F. Korol, Mansfield, Ohio, assignor to Bord-Warner Corporation, Chicago, Ill.

Filed Sept. 26, 1974, Ser. No. 509,620

Term of patent 14 years

Int. Cl. D23—02

U.S. Cl. D23—65

FIG - 8

FIG - 9

FIG - 10

FIG. 1 is a perspective view of a water closet showing my new design;

FIG. 2 is a right side elevational view thereof;

FIG. 3 is a front elevational view thereof;

FIG. 4 is a top plan view thereof;

FIG. 5 is a left side elevational view thereof;

FIG. 6 is a rear elevational view thereof;

FIG. 7 is a bottom plan view thereof;

FIG. 8 is a perspective view of a modified form of the water closet shown in FIG. 1;

FIG. 9 is a right side elevational view of FIG. 8;

FIG. 10 is a front elevational view of FIG. 8;

FIG. 11 is a top plan view of FIG. 8;

FIG. 12 is a left side elevational view of FIG. 8;

FIG. 13 is a rear elevational view of FIG. 8; and FIG. 14 is a bottom plan view of FIG. 8.

I claim:

The ornamental design for a water closet, as shown and described.
